ILLUMINABLE COSMETIC MIRROR OR THE LIKE

Stanford Pavenick, South Orange, N. J., assignor to Aljen Manufacturing Corp., New York, N. Y., a corporation of New York

Application March 3, 1955, Serial No. 34,862

Term of patent 14 years

(Cl. D86—10)

Fig. 1 is a front perspective view of an illuminable cosmetic mirror or the like showing my new design with its lid raised;

Fig. 2 is a left side elevational view of said mirror with the lid down;

Fig. 3 is a top plan view of said mirror with the lid down;

Fig. 4 is a rear elevational view of the mirror with the lid down; and

Fig. 5 is a bottom view of the mirror on a reduced scale.

The dominant features of my invention are shown in full lines.

I claim:

The ornamental design for an illuminable cosmetic mirror or the like, substantially as shown and described.
